HARRY T. KRAKAU, OF CLEVELAND, OHIO, ASSIGNOR TO THE NATIONAL MALLEABLE CASTINGS COMPANY, OF CLEVELAND, OHIO, A CORPORATION OF OHIO.

DRAFT-GEAR AND BUFFING MECHANISM.

No. 900,023.

Specification of Letters Patent. Patented Sept. 29, 1908.

Application filed June 17, 1907. Serial No. 379,376.

To all whom it may concern:

Be it known that I, HARRY T. KRAKAU, of Cleveland, Cuyahoga county, Ohio, have invented a new and useful Draft-Gear and Buffing Mechanism, of which the following is a specification, reference being had to the accompanying drawing, in which—

Figure 1 is a plan view partly in section showing my radial draft gear; Fig. 2 is a vertical longitudinal section partly in side elevation; Figs. 3 and 4 are sectional detail views on the lines III—III and IV—IV, respectively, of Fig. 1; Fig. 5 is a detail view partly in longitudinal section showing the manner of connecting the coupler to the extension shank, together with the plates by which the coupler is connected to the buffer; Fig. 6 is a side elevation partly in longitudinal section on a larger scale showing the novel manner 20 of carrying and supporting the buffer shank and connecting it to the spring casing and to the coupler shank; Fig. 7 is a vertical cross section on the line VII—VII of Fig. 6; Fig. 8 is a detail plan view showing the buffer and 25 its carry irons; Fig. 9 is a vertical longitudinal section on the line IX—IX of Fig. 8; Fig. 10 is a vertical longitudinal section on the line X—X of Fig. 1, but on a larger scale, and Fig. 11 is a vertical cross section through 30 the spring casing of the buffer and the coupler shank extension, showing the manner of their connection, the section being on the line XI—XI of Fig. 2.

The purpose of my invention is to provide, 35 a draft gear having a radially swinging coupler and a radially swinging buffer related so as to operate together and to afford efficient means by which both the coupler and buffer can adapt themselves to the motion of the car truck as it passes around curves, and will operate properly under all such conditions of use.

The device is especially adapted for passenger cars and it accomplishes the desired 45 results with great efficiency and simplicity of mechanism.

2 represents the car coupler, whose shank 3 has a long rearward extension 3' which may be made in one piece with the main portion 50 of the shank, but is preferably a separate piece and is connected therewith as shown in Fig. 5, the extension 3' having a socket 4 at its forward end into which the coupler shank 3 is fitted. This socket has opposite lateral 55 recesses in which connecting plates 5 are

fixed, preferably by bolts 6 which pass through the plates and through the socket and the contained coupler shank. The plates extend upwardly and serve to give a floating connection between the coupler 60 shank and the buffer mechanism, as explained below.

The extension 3' at its rear end is curved upwardly and is connected by a yoke or other suitable device 7 with a draft rigging 8 set 65 between the sills of the car, and the coupler shank is also preferably provided with a sliding socket 9, from which guiding connections 9' are extended to the truck in a manner as heretofore known. These guiding 70 connections are preferably made in the form of telescopically fitted parts containing springs 9^a, and they are pivotally connected at 9^b and 9^c to the socket 9 and to the truck-frame of the car, respectively. A tail-bolt 75 may be substituted for the yoke 7 and any suitable form of draft rigging, whether frictional or otherwise, may be employed at 8. The coupler shank is supported by carry-irons 10 which extend between the sills of the 80 car and may be supported by hangers 11.

The coupler shank extension 3' has a vertical pivot pin 12 which connects it to the yoke 7, so that when the car is passing around curves the coupler and its shank will swing 85 radially on the axis of the pin 12 and will constantly be kept thereby approximately at the central portion of the railway track.

13 is the face plate of the buffer, having a rearwardly extending forked shank formed 90 with two parallel arms 14, 14^a, as shown in Figs. 6 and 7. Between these arms of the buffer extends a transverse carry-iron 15 which is curved as shown in Fig. 8, and is connected to the center sills 16 and intermediate sills 16^a of the car, preferably in the manner shown in Fig. 1, being preferably riveted thereto by rivets 17, and preferably having at its ends shoulders 18 against which the ends of the center sills and intermediate sills abut, so that the stress of buffing is transmitted directly to these sills and the sheering strain is removed from the rivets. The front edge of the carry-iron 15 is so related to the rear bearing surface of the 105 buffer face plate as to be equidistant from all of the contacting points b, b so that when the buffer is moved back to the limit of compression of the springs it will engage at all points 110 at once with the carry-iron, and thus will

transmit the stress thereto equally and regularly.

The carry-iron 15 being secured firmly to the center sills is well adapted to take the upward strain from the buffer and to provide a durable structure, whereas in constructions wherein the upward strain is transmitted to the underside of the platform end-sill, that sill is often not strong enough to resist it. 5 Independently of its use as a carry-iron, the part is of value because by connecting the center-sills and receiving the stress from the buffer it gives a strong construction. By 10 thus transmitting the severe buffing strain to the carry-iron, it is taken up by a substantial part of the car frame and is so far forward relatively to the buffer that there will be no substantial bending action upon the latter.

The rear end of the forked buffer shank is 20 held by a spring casing 19, preferably made in two longitudinally divided parts connected by bolts 20, and the said shank has at the outer surfaces of its arms 14, 14^a sockets B shown by full lines in Figs. 8 and 9 and by 25 dotted lines in Fig. 6, to which projections c, c on the casing extend so that when the parts of the casing are held by the bolts they will be clamped firmly and rigidly upon the arms of the buffer shank, a filler piece 19' being interposed between the arms. The 30 contacting surface a of the spring casing and arm 14 are preferably tapered so that these parts will draw tightly together and make a firm union. The spring casing extends rearwardly from the buffer shank, and fits telescopically over a rear spring casing 21 which 35 extends within the spring casing 19 and contains interposed buffing spring mechanism which is compressed by backward motion of the buffer shank and the spring casing 19. 40 The spring mechanism comprises preferably two springs 22 and 22^a, the spring 22^a being an auxiliary spring of less capacity than the main spring 22, and being designed to exert a 45 constant tension sufficient to force the buffer and its shank outwardly and to keep it in contact with the corresponding buffer of another car, even when the coupler shank is under draft and is drawn out to its full extent. 50 This spring also aids the main spring 22 in the work of buffing under compression.

The rear spring casing 21 has a rearward extension 21^a formed at its end with a forked guide portion 21^b which fits over a guiding segment 23. This segment is a strong frame 55 preferably a casting, which is riveted at its ends to the center sills 16 of the car so as to receive the stress of buffing. It is in line with and forms part of the end sill of the car 60 frame.

The engagement of the buffer with the coupler shank is effected by the plates or 65 projections 5 which, extending upwardly from the coupler shank as above described, fit on opposite sides of the spring casing 19,

as shown in Fig. 11, so as to permit independent longitudinal motion of the coupler shank and buffer. These plates 5 are preferably provided with shoulders 24, 24', which serve respectively to support and confine the spring 70 casing of the buffer; and the plates 5 bear against shoulders 25 on the spring casing (Figs. 6 and 11) so as to transmit thereto the buffing stresses which are applied to the coupler. This manner of engaging the coupler with the buffer by means of upwardly extending projections from the coupler constitutes a very strong and reliable device and transmits the stress to the buffer at its central portion. Like advantages in this regard 80 are obtained by the forking of the arms 14, 14^a of the buffer shank, for by using two such arms the buffing stresses are applied uniformly to the front buffer plate at its top and bottom portions, and there is, therefore, no bending moment thereof during the act of 85 buffing. This forking of the buffer shank enables me to elevate the position of the buffer so as to bring its shank into line with the frame of the segment 23 and to apply the 90 stress thereto centrally. The forking of the portion 21^b so that it forms an open socket 95 engaging the segment is advantageous, as it enables these parts to be easily separated for purposes of repair, all that is necessary to disconnect the buffer being to remove the plates 5, separate the parts of the spring casing 21, and to draw the buffer mechanism forward from the segment.

For the purpose of taking up the wear, I 100 prefer to provide a wear plate 26 between the segment 23 and the socket 21^b.

To provide means by which the draft of the cars can be transmitted to the buffing mechanism in case the coupler or its shank 105 should break, I apply safety chains 27 to the buffer as shown in Fig. 2 so as to connect with the safety chains of an adjoining car. In case the coupler should be broken, these chains will take the stress of draft of the cars 110 and, transmitting it to the buffer, will draw the spring casing 22 forwardly until it engages the rear of the carry-iron 15, to which the draft is thus transmitted. This constitutes a novel and very efficient safety device. 115

Within the scope of my invention as defined in the claims, the parts of the apparatus may be modified in various ways, since

What I claim is:

1. A laterally swinging draft member 120 mounted for longitudinal movement in buffing and draft, and a laterally swinging buffer mounted above the draft member on an independent support, and engaged with the draft member by a sliding connection which 125 engages the sides of the buffing mechanism, substantially as described.

2. A laterally swinging draft member 130 mounted for longitudinal movement in buffing and draft, and a laterally swinging buf-

fer mounted above the draft member on an independent support and engaged with the draft member by a sliding connection which engages the sides of the buffing mechanism 5 and is fixed to the sides of the draft member, substantially as described.

3. A laterally swinging draft-member mounted for longitudinal movement in buffing and draft, and a laterally swinging buffer mounted above the draft-member and engaged therewith by a connection which engages the sides of the buffing mechanism, said connection having a rear bearing against the buffer and being free to move independently 10 on its forward side; substantially as described.

4. A laterally swinging T-shaped buffer having its transverse member rigid with the shank and adapted to engage a corresponding member on the buffer of another car to hold the buffers in alinement, in connection 20 with a carry-iron on which it can move laterally and longitudinally, said buffer having arms extending above and below the carry-iron and connected at the rear to spring 25 mechanism; substantially as described.

5. A laterally swinging buffer having at its rear an open socket, a curved segment against which the open socket fits, and means 30 forward of said segment to hold the buffer in operative relation thereto, substantially as described.

6. A buffer having divided arms and a spring casing formed in sections fixed together around said arms; substantially as described.

7. A laterally swinging draft member having a coupler shank and a rearward extension, one of said parts being formed with a 40 socket and the other part extending into the socket, connecting pieces extending from said socket to a buffer, and means by which the connecting pieces, socket and shank are held together; substantially as described.

45 8. A laterally swinging draft-member mounted for longitudinal movement in buffing and draft, a buffer, and means for engaging the draft-member with the buffer, comprising upward projections having supporting portions for the buffer and adapted to permit independent rear movement of the buffer and transmitting rear movement of the draft member to the buffer spring, substantially as described.

55 9. A laterally swinging draft-member

mounted for longitudinal movement in buffing and draft, a buffer, and means for engaging the draft-member with the buffer comprising upward projections having supporting portions for the buffer and adapted to 60 permit independent and conjoint longitudinal motions between the draft-member and the buffer, said supporting portions engaging the spring casing of the buffer; substantially as described.

65 10. A carry iron having a front convex edge constituting a buffer bearing surface, and provided at each end with a shoulder having a rear face for engagement with the end of a center sill, substantially as described.

70 11. The combination of a buffer and its springs and a carry-iron for the buffer, said carry-iron being adapted to resist back motion of the buffer and to take up the buffing strain only at the limit of compression of the 75 springs; substantially as described.

12. A buffer in combination with longitudinal sills and a connection between the sills and in advance of the buffer springs against which the buffer abuts at the end of 80 its rearward motion; substantially as described.

13. A T-shaped buffer having its transverse member held rigidly at right angles to its shank and constructed to engage the 85 transverse member of an opposing buffer and maintain the shanks in alinement, said shank having a slot closed at its front end and open at its rear end to pass over a carry iron, substantially as described.

90 14. A buffer spring case constituted of telescopically fitted parts, the front part having internal projections to fit sockets in a buffer shank, and being divided longitudinally for attachment to a buffer shank.

95 15. A buffer carry-iron extending transversely of the car frame back of the front end of the platform and adapted to receive the buffing stress from the buffer only at the end of its spring compression; substantially as 100 described.

16. A coupler shank having lateral vertical recesses for reception of buffer-connection plates; substantially as described.

In testimony whereof, I have hereunto set 105 my hand.

HARRY T. KRAKAU.
